United States Patent Office

Des. 195,861
Patented Aug. 6, 1963

195,861

FLOWER HOLDER

George M. Frybergh, New York, N.Y., assignor to Prime Premiums, Inc., New York, N.Y., a corporation of New York

Filed Feb. 23, 1962, Ser. No. 68,937

Term of patent 7 years

(Cl. D35—3)

FIG. 1

FIG. 3

FIG. 1 is a top plan view of a flower holder embodying my new design;

FIG. 2 is an enlarged fragmentary cross sectional view thereof taken on the lines 2—2 of FIG. 1; and

FIG. 3 is an enlarged fragmentary top plan view taken in the area 3 of FIG. 1.

I claim:

The ornamental design for a flower holder, substantially as shown.
